UNITED STATES PATENT OFFICE.

WILLIAM BUNTING, JR., OF BROOKLINE, MASSACHUSETTS.

COMBINATION SUPPLY AND WASTE APPARATUS.

No. 922,253.

Specification of Letters Patent.

Patented May 18, 1909.

Application filed October 31, 1906. Serial No. 341,400.

To all whom it may concern:

Be it known that I, WILLIAM BUNTING, Jr., of Brookline, county of Norfolk, State of Massachusetts, have invented an Improvement 5 in Combination Supply and Waste Apparatus, of which the following description, in connection with the accompanying drawings, is a specification, like characters on the drawings representing like parts.

19 This invention relates to certain improvements in the combination supply and waste apparatus disclosed in my prior patent #682,453, dated September 10, 1901, and which is especially adapted for use in residences where self closing faucets are not desired. In public buildings, however, self-closing faucets are usually required, and while I have attempted to make the valve apparatus shown in this patent self closing 25 by the application of springs, I have been unable to do so in a practical manner.

The primary object of my invention is to produce an apparatus similar to that disclosed in said prior patent in which the water supply valves shall be self-closing and which cannot be held open by the insertion of a plug or other holding device.

A further object of my invention is to simplify said prior apparatus so that it may be 30 easily installed, and so that the use of stuffing boxes may be avoided and the cost of manufacture of the fitting may be materially reduced.

Another object of my invention is to produce an apparatus of the above described character which is of slighty appearance and easy of operation.

I accomplish these objects by the means shown in the accompanying drawing, in 35 which,

Figure 1 is a central vertical section of a set bowl provided with a fitting comprising my invention, the latter being shown as a partial section on line 1-1 of Fig. 4. Fig. 2 is a central section of the upper end portion of the fitting taken on the line 2-2 of Fig. 3. Fig. 3 is a front elevation and partial section on the line 4-4 of Fig. 1, showing one of the operating handles in the open position. Fig. 4 is a section on the line 4-4 of Fig. 1. Figs. 5, 6, 7 and 8 are detail views of the valve operating handles. Fig. 9 is an enlarged section on the line 9-9 of Fig. 4. Figs. 10 and 11 are sectional detail views taken on the lines 10-10 and 11-11, respectively, of Fig. 4. Fig. 12 is a vertical sec-

tional view, similar to Fig. 4, of a modified form of my invention. Fig. 13 is a vertical section on the line 13-13 of Fig. 12. Fig. 14 is a cross section on the line 14-14 of Fig. 12. Fig. 15 is a plan view of the operating handle which I employ in this connection. Fig. 16 is a detail view of the valve-lever engaging means.

As shown in Fig. 1 of the drawing, the basin *a* is provided with the usual waste valve *b*, said valve being connected to the vertically movable operating rod *c* which extends up through the water supply fitting, as hereinafter more fully described, said rod 70 having an operating handle *c'* secured to its upper end and said waste valve being adapted to be closed and opened upon the lifting and lowering of said rod, the connecting mechanism therebetween being of a character well known in the art.

Referring to Figs. 1 to 11 inclusive, the main body or discharge casing *d* of the fitting, which is fixed in the basin slab *b'* and extends below the under side thereof, is provided with a mixing chamber *d'*, and an inlet casing *e* is connected to the lower end thereof by a union *d'*, said inlet casing forming an extension of chamber *d'* and having horizontally and oppositely disposed hot and cold water supply 85 pipes *e'*, *e''*, connected to the sides thereof. Valve casings *f*, *g* are respectively connected to said supply pipes *e'*, *e''*, and spring pressed valves *h*, *i*, are provided in said casings respectively. Said valves are adapted to be 90 opened against the action of their springs by means of a compound lever mechanism *h'*, *h''*, and *i'*, *i''*, respectively, upon pressing downwardly on the outer ends of the outermost levers *h'*, *i''*, said mechanism being substantially identical to that of the well known

"Doherty" ball-cock, in which a weighted float rod is connected to the end of the part which corresponds to the lever *h'*, *i''*, herein shown. The lower end or bottom of the 100 casing *e* and the upper end or top of the casing *d*, are respectively provided with openings which are in central alinement with the chambers therein, the opening in the casing *e* being provided with a surrounding boss *e'*, 105 into the bore of which a casing tube *j* is tightly screwed, so that a rigid, water-tight connection is provided between the lower end of said tube and the casing *e*. Said tube *j* extends upwardly through said mixing 110 chamber and is tightly connected by a driving fit to the upper end of casing *d* in the bore

in the upper end thereof. The upper portion of casing d is preferably provided with a partition wall d^6 which extends forwardly into the discharge spout d^6 , so that an open connection is provided between the space above said wall and the spout, said tube j passing through said wall d^6 and being tightly fitted therem, but in case there should be any leakage through this joint into the space between said wall and the casing, such leakage would be carried off through the spout, so that there would be no danger of leakage through the joint between the upper end of the body and said tube j .

15 A tubular valve stem k is fitted within the tube j , a second tubular valve stem m is fitted within the tube k , and the waste operating rod c is fitted within the tube m , said tubular stems k and m and said rod c all being adapted to slide freely, vertically, with relation to each other. The lower end of the outer valve stem k extends a short distance below the end of the boss e^3 and a bracket n , having a semi-cylindrical recess therein, is fitted and rigidly connected to said stem k by screws n^1 or any other suitable means. The boss e^3 is provided with a semi-cylindrical extension e^4 , against the edges of which the side edges of the bracket n bears, so that said stem k is held from rotation in either direction. A finger n^2 on the bracket n is adapted to bear on the outer end of the valve operating lever h^2 , as shown, so that when said stem k is moved downwardly said valve 35 will be opened. The stem m extends a short distance below the lower end of stem k , and a bracket o is fitted onto the lower end thereof and is held thereon by a screw o^1 . A projecting finger o^2 on said bracket o , is adapted 40 to engage the outer end of the lever i^2 , so that upon downward movement of the stem m the valve i will be opened.

A pair of operating handles p and q , which may be respectively marked to indicate the hot and cold water supply, are provided, said handles having semi-cylindrical body portions p' , q' , respectively, which are adapted to be fitted together to make a complete cylinder, the abutting edges thereof being vertical. The lower end portion of the body p' is provided with a projecting ring portion p^2 , having a bore in which the upper end of the outer stem k is fitted and to which it is rigidly and permanently connected by suitable means, and the upper end of the body portion q' is provided with a similar projecting ring portion q^2 , in which the upper end of the stem m is likewise fitted and permanently connected. The internal diameter of each body portion p' , q' and the external diameter of each ring portion p^2 , q^2 , is the same, so that when said handles are fitted together as shown in Figs. 3, 4 and 5, they may slide vertically with relation to each other, each ring portion p^2 , q^2 , entering and sliding with-

in the opposite body portion q' , p' respectively. These parts are thus held together practically as one piece and cannot turn one with relation to the other, as their adjacent edges engage, and, as the tube k is held from turning by the boss e^4 , the stem m is thus held from turning thereby. The thickness of each projecting ring portion p^2 , q^2 , is approximately one-third the length of the body portions p' , q' , so that a space also approximately one-third of said length is provided between said projections. The distance from the lower ends of said body portions to the upper end of casing d is also approximately one-third of said length. If, therefore, it is desired to open the valve i , the handle q is pressed downwardly until the lower end of its body portion q' engages casing d , and the projection q^2 touches or nearly touches the projection p^2 , moving finger o^2 85 and the operating levers of said valve to the dotted position of Fig. 4, in which position the valve is fully open. When the handle is released the valve spring will automatically close the valve and return the parts to the full line position. As the projecting ring portion q^2 is inclosed by the body portion p' in all positions of the former no open spaces are provided into which an instrument might be inserted, so as to hold the valve i 95 open. If it is desired to open the valve h , the handle p will be pressed downwardly and this valve will also be fully opened when the handle is moved to the position shown in Fig. 3, in which position the lower end of body portion p' will engage casing d , while its upper end will still extend slightly above the lower side of the ring portion q^2 , and the upper side of the ring portion p^2 will still extend slightly above the lower end of the body 100 q' , so that there will be no opportunity to insert an instrument between said ring and body portion to hold the valve h open. Obviously both handles p and q may be pressed downwardly simultaneously, so that the 110 mixed hot and cold water will be delivered through the discharge spout d^6 . As devices of this character must usually be installed by a plumber who is somewhat unfainiliar with the apparatus, it is necessary to have fittings 115 of this sort assembled beforehand, as far as possible, so that the final installation will be simplified and the liability of mistakes being made reduced to a minimum. The connection, therefore, between the tube j and the 120 casing e is practically made a permanent connection, and is made previous to installation. The connection between the upper end of said tube j and the casing d must, therefore, be made after said casing d has been inserted in the slab, while a reasonably tight fitted joint is all that is necessary, at this point, yet I prefer to have it a driving fit 125 so that the parts will be securely assembled and there will be no leakage even if a shower 130

hose is attached to the nozzle. The most convenient method of forcing the upper end of tube j into the opening therefor in the upper end of casing d is by means of the coupling ring d^2 . After the tube j has been fixed in the lower casing e , the parts are brought together until the threads of the ring d^2 engage those of the casing d , so that, when the ring is screwed onto the casing d the tube j will be forced into place at the same time that the casings are connected. The handles p and q are likewise permanently connected to their stems k and m and the brackets n and o are connected after said stems have been inserted. The use of stuffing boxes is thus avoided and the installation of the apparatus greatly simplified.

In Figs. 12 to 16 inclusive I show a somewhat simplified form of my invention, in which one of the water supply valve operating stems is eliminated. In this form of my invention the inlet casing e^0 , inlet valves h^0 and i^0 , and their operating mechanisms, h^{20} , i^{20} , the waste valve operating rod c^0 and the inclosing tube j^0 are all substantially identical with the corresponding parts previously described. The discharge casing d^0 is also similar to the discharge casing d , except that it is provided with an upwardly extending annular boss d^3 on its upper end. A single tubular valve stem m^0 is provided which is slidably fitted within the tube j^0 and a handle u is secured, by means of an integral depending body portion u' , to the upper end of said tube j^0 , said body portion being cylindrical and adapted to slide or rotate freely in the boss d^3 of the discharge casing. The rod c^0 passes through said portion u' , as in the form of my invention already described. Said body portion u' is provided with a laterally projecting lug u^2 , which is adapted to be fitted and to slide vertically in any one of three vertical slots d^7 , d^8 and d^9 , formed on the inner side of the boss d^3 . A collar v , having a horizontally projecting circular flange v' at its lower end, is removably secured to the lower end of the stem m^0 , said flange having a portion thereof cut away so that it extends through slightly more than a semicircle and is adapted to engage the ends of the valve operating levers i^{20} , h^{20} , which are oppositely disposed with relation thereto, simultaneously, when held in the full line position of Fig. 16, and as also shown in Fig. 12. The springs of the supply valves normally hold the valve stem u in a position in which the lug u^2 is above the upper end of the boss d^3 , but in which the portion u' extends to the recess inclosed by said boss, so that the handle u may be turned horizontally to bring said lug directly over any one of the three vertical slots d^7 , d^8 , d^9 , in either of which positions, but in no other, the handle and stem may be pushed downwardly, while it is held from rotation. If the handle is adjusted in

a position in which the lug u^2 is in line with the slot d^8 , the collar v will assume the full line position of Fig. 16, so that when the handle u is pushed downwardly both valves will be opened simultaneously and mixed hot and cold water will be delivered from the discharge casing. When the handle is turned so that the lug u^2 is in line with the slot d^9 the collar v will be in the dotted position shown in Fig. 16, so that when the handle is pressed downwardly in this position the cold water valve i^0 will be opened without opening the valve h^0 , and when the handle is turned to the opposite position to that shown in dotted lines Fig. 16, and pushed downwardly, the hot water valve h^0 will alone be opened, the cut away portion of the flange v' being in these positions directly over one of said valve mechanisms h^{20} or i^{20} . The words "Cold", "Mixed" and "Hot" are preferably placed in the upper side of the handle, as shown, so that when the handle is turned into a position in which any one of these words are in position to be read from the front and the handle is pushed downwardly, the corresponding valve or valves will be operated. With this arrangement there is no place above the basin slab in which an instrument may be inserted to hold the valve open. The parts of this form of my invention are assembled in substantially the same way as that already described, but as they are fewer in number they are easier to assemble and the cost of producing this form is less.

Having thus described my invention, what I claim as new and desire to secure by Letters Patent is:—

1. A water supply apparatus comprising an outlet casing adapted to be mounted in a basin slab, and having a transverse discharge port and an opening in its upper end, an inlet casing having transverse inlet ports and an opening in its lower end, a tube located in the bores of said casings and rigidly mounted at one end in the opening of one of said casings, and a screw-threaded coupling for connecting the adjacent ends of said casings and simultaneously forcing the other end of said tube into tight connection with the other casing about the opening thereof, substantially as described.

2. A water supply apparatus comprising an outlet casing adapted to be mounted in a basin slab, said casing being open at its bottom and having a discharge port, an inlet casing removably connected to the lower end on said outlet casing and having a lateral supply port, said outlet casing having an opening in its upper end and said inlet casing having a similar opening in its bottom, a tube extending through said casings and having its ends respectively mounted in said openings, said tube having a permanent connection with one casing and a sliding fit connection with the other, and a valve stem

extending through said opening and said tube and having a handle at its upper end and valve operating devices at its lower end, substantially as described.

5. 3. A water supply apparatus comprising a casing having a mixing chamber provided with a supply and a discharge port, a self-closing valve for controlling said supply port, a tube extending through said casing 10 from top to bottom thereof and having a rigid connection therewith at each end, a vertically movable valve stem located in said tube, and operating devices for said valve arranged to be engaged by said stem 15 at its lower end to support the same, and movable thereby upon downward movement thereof to open the valve, substantially as described.

4. A water supply apparatus comprising 20 a discharge casing, hot and cold water supply pipes leading thereto, a longitudinally movable and rotatably adjustable valve stem, valve mechanisms for separately controlling said supply pipes disposed adjacent said 25 stem, and transversely extending engaging means carried by said stem disposed to engage said valve mechanisms simultaneously or separately in different positions of adjustment of said stem, substantially as described.

5. A water supply apparatus comprising a discharge casing, hot and cold water supply pipes leading thereto, a longitudinally movable and rotatably adjustable valve stem, 35 valve mechanisms for separately controlling said supply pipes disposed adjacent said stem, and transversely extending engaging means carried by said stem disposed to engage either of said valve mechanisms to 40 operate them separately in different positions of adjustment of said stem, substantially as described.

6. A water supply apparatus comprising a discharge casing, hot and cold water supply 45 pipes leading thereto, a longitudinally movable and rotatably adjustable valve stem, valve mechanisms for separately controlling said supply pipes disposed adjacent said stem, and a transversely extending projection 50 extending partially about said stem and movable into engagement with either of said valve mechanisms separately or simultaneously in different positions of adjustment of the stem, substantially as described.

55. 7. A water supply apparatus comprising a discharge casing having hot and cold water supply pipes leading to the lower end thereof, a longitudinally movable, rotatably adjustable valve stem having an operating handle 60 at its upper end, valve mechanisms disposed adjacent the lower end of said stem for separately controlling said supply pipes, and a transversely extending projection on the lower end of said stem disposed to engage 65 either of said valve mechanisms to operate

the same upon downward movement of the stem in certain positions thereof, substantially as described.

8. A water supply apparatus comprising a discharge casing, hot and cold water supply 70 pipes leading thereto, a longitudinally movable, rotatably adjustable valve stem, valve mechanisms for separately controlling said supply pipes disposed adjacent said stem, a transversely extending engaging means on 75 said stem disposed to engage either of said valve mechanisms in certain positions of adjustment of the stem, and to operate the same upon longitudinal movement thereof, and means for holding said stem from rotation while it is being moved longitudinally in either of said positions, substantially as described.

9. A water supply apparatus comprising a discharge casing, hot and cold water supply 80 pipes leading thereto, a rotatably adjustable 85 valve stem, valve mechanisms for separately controlling said supply pipes disposed adjacent said stem, a transversely extending engaging means on said stem disposed to engage either of said valve mechanisms in certain 90 positions of adjustment of the stem, and means permitting longitudinal movement of said stem to operate either of said valve mechanisms when in the corresponding position of adjustment and for preventing said movement in other positions of adjustment, 95 substantially as described.

10. A water supply apparatus comprising a discharge casing, hot and cold water supply 100 pipes leading thereto, a longitudinally movable, rotatably adjustable valve stem, valve mechanisms for separately controlling said supply pipes disposed adjacent said 105 stem, a transversely extending engaging means on said stem disposed to engage either of said valve mechanisms in certain positions of adjustment of the stem, and to operate the same upon longitudinal movement thereof, a guiding support for said stem having a series 110 of guide grooves therein extending longitudinally of the stem, and a projection on said stem adapted to move vertically in either of said grooves to guide said engaging means into engagement with said valve mechanisms 115 respectively, substantially as described.

11. A water supply apparatus comprising a discharge casing, hot and cold water supply 120 pipes leading thereto, a longitudinally movable, rotatably adjustable valve stem, valve mechanisms for separately controlling said supply pipes disposed adjacent said 125 stem, a transversely extending engaging means on said stem disposed to engage either of said valve mechanisms in certain positions of adjustment of the stem, and to operate the same upon longitudinal movement thereof, a guiding support for said stem having a series 130 of guide grooves therein extending longitudinally of the stem, a projection on said stem

adapted to move vertically in either of said grooves to guide said engaging means into engagement with said valve mechanisms, respectively, and means for normally holding said stem with its said projection above the entrance to said grooves to permit the same to be turned to bring the projection into alinement therewith respectively, substantially as described.

10 12. A basin fitting comprising a bowl having a waste valve, a casing having a chamber provided with a supply port, and discharge port leading to said bowl, valve mechanism for controlling said supply port, a vertically movable, tubular stem having a transverse

projection at its lower end for engaging said valve-mechanism to operate the same upon vertical movement of said stem and having a transverse operating handle at its upper end, and a rod, having an operating handle at its upper end, extending through said stem and movable therein to operate said waste valve, substantially as described.

In testimony whereof, I have signed my name to this specification, in the presence of 25 two subscribing witnesses.

WILLIAM BUNTING, JR.
